UNITED STATES PATENT OFFICE.

WILLIAM H. COLLIER, OF JACKSON, TENNESSEE.

CARBURETOR FOR INTERNAL-COMBUSTION ENGINES.

Application filed April 9, 1925. Serial No. 21,828.

To all whom it may concern:

Be it known that I, WILLIAM H. COLLIER, a citizen of the United States, residing at Jackson, in the county of Madison and State 5 of Tennessee, have invented certain new and useful Improvements in Carburetors for Internal-Combustion Engines, of which the following is a specification.

This invention relates to carburetors for 10 internal combustion engines which are required to work at widely varying speeds and under variable load conditions such as are met with in the operation of automobiles.

15 One of the objects of my invention is to provide a carburetor having a variable control element, operable by the usual throttle control lever at the steering wheel, which performs the dual function of a throttle 20 valve and a variable fuel supply valve and under every condition of speed and load delivers a proper fuel mixture to the engine cylinders. One of my purposes is to dispense with the separate throttle valve and 25 air and fuel control mechanism now used and the necessity for auxiliary air supply devices and to reduce the entire engine control to a single manually controlled element. A further object is to dispense with the use 30 of a vacuum tank and to connect the carburetor by a pipe leading directly to the gasoline supply tank. To this end I have devised a carburetor which maintains at all times a degree of vacuum, or sub-atmospheric 35 pressure at the jet orifices which varies in accordance with the controlled speed of the engine and thereby delivers the proper quantity of fuel to the vacuum chamber under all of the varying conditions 40 of load and engine speed without any tendency to flooding during an idling period or to produce too rich or too lean a mixture under varying speed conditions. Another object is to produce a carburetor 45 which cannot flood or leak under any conditions. A further purpose is to produce a carburetor which will deliver into the engine a less amount of fuel mixture under all conditions of load and speed than can be obtained 50 at present and also to furnish a uniform mixture under all conditions.

In the following description I shall refer to the accompanying drawings, in which:

55 Figure 1 illustrates the manner in which my carburetor may be connected to the engine manifold and directly with the fuel

supply tank usually secured to the rear of the vehicle; Figures 2 and 3 are longitudinal sectional views of a carburetor embodying my invention; Figure 4 is a longitudinal section of a modified form of my carburetor; and Figure 5 is an enlarged fragmentary sectional view of the form of metering plug shown in Figure 3; and Figure 6 is a fragmentary enlarged view of the carburetor shown in Figure 2 but with the parts in maximum speed position.

The carburetor comprises two parts, an inner body portion and an outer revolute casing movable longitudinally thereover. 70 The body portion is provided at one end with a liquid fuel passage 2, internally threaded for connection to the gasoline line and at the opposite end with a main mixing chamber 3, exteriorly threaded for connection 75 with the engine manifold, indicated at 1.

The fuel passage 2 is connected by a plurality of radiating ducts 4 with the circumferential surface of the body, a metering 80 plug 5 with an orifice suited to the particular engine being intercalated in said fuel passage. The main mixing chamber 3 is likewise connected with the circumferential surface of the body by means of apertures 6 85 which open into a channel 15 formed between the valve seat 7 and the inner wall of the casing, the channel 15 constituting a preliminary mixing chamber.

The tapering valve seat 7 lies between 90 the mixture apertures 6 and the mouths 4^a of the fuel ducts. The inner flaring surface 8^a of the casing which cooperates with the tapering seat 7 constitutes a throttle valve 95 for the carburetor. The casing is adjustable longitudinally of the carburetor body for the purpose of varying the air intake and fuel supply. As a means of accomplishing this adjustment I have shown a coarse thread engagement 9, so that the rotation of the casing causes it to travel longitudinally.

Inasmuch as I do not employ a vacuum tank or a float chamber it is essential to subject the liquid column in the gasoline line to 105 a sub-atmospheric pressure at all times during the running of the engine. For this purpose the fuel ducts 4 terminate in a vacuum spray chamber 15, constituting a preliminary mixing chamber, formed between the carburetor body and an enlarged 110 portion of the casing 8. The air inlet is

formed between the inner face 13 of a flange 5 extending inwardly from the casing, constituting an air valve, and a sloping or tapering complementary surface 12 on the body. The inclinations of the throttle valve seat 7 and of the sloping surface 12 which cooperates with the air-inlet valve 13, bear a definite relation to each other such that sub-atmospheric pressure in the main mixing chamber 3 remains substantially constant for all speeds of the engine while that in the preliminary mixing chamber 15 increases with the speed of the engine from a predetermined minimum to the maximum 10 existing in the mixing chamber. The slant or obliquity of the tapering surface 12 is such that for any position of the air valve 13, corresponding to a definite engine speed, the air inlet permits the ingress of just the proper volume air while the tapering valve seat 7 cooperates with the throttle valve 8^a to provide a passage between the main mixing chamber 3 and the preliminary mixing chamber 15, of such dimensions that the 15 degree of vacuum or sub-atmospheric pressure in the preliminary mixing chamber 15 causes the jets of gasoline issuing from the mouths 4^a of the fuel ducts to be so proportioned to the volume of air as to produce 20 the proper mixture in the chamber 3.

A different rate of opening of these valves is essential to the preservation of the predetermined minimum sub-atmospheric pressure in the preliminary mixing chamber 15 25 and the proportional increase of the sub-atmospheric pressure therein as the engine speed increases so that the gasoline will be lifted and issue from the jet orifices 4^a in proportion to the increase in the volume of air to maintain the proper fuel mixture at all speeds. In the particular construction illustrated in the accompanying drawings, I have found that the relative inclinations of the sloping face 12 of the air inlet and of 30 the seat 7 of the throttle valve should be at the respective angles with the longitudinal axis of the body the ratios of whose tangents is as 1 to 3. Constructed with these values I have maintained a sub-atmospheric 35 pressure of substantially 15 inches or 7¹/₂ pounds in the main mixing chamber 3 at all speeds while the sub-atmospheric pressure in the preliminary mixing chamber 15 surrounding the jet orifices, increased proportionately with the speed from a minimum of substantially 1 inch to a maximum at full speed of 15 inches.

The valve casing 8 is provided with an arm 18 to which is connected the link 19 40 leading to the throttle control lever and the foot lever at the steering stem. In operation, the valve casing may be moved to the full choke position shown in Fig. 3, with the inner edge of the air valve 13 abutting 45 the abutment 14, thereby completely cutting

off the air valve. As the engine is turned over by the starter gasoline is drawn through the jet orifices 4^a and the valve casing is then immediately thrown back to the idling position shown in Figure 2 in which the air and throttle valves are open only very slightly. The engine speed may then be increased as desired by rotating the valve casing. When the valves are in the position shown in Figure 6, the maximum speed 50 is attained since the annular area between the air valve 13 and the face 12 is then equal to that between the valve 13 and the abutment 14. At this time the sub-atmospheric pressure in the preliminary mixing chamber 55 15 is equal to that in the main mixing chamber 3. A continued movement of the valve casing from this point of maximum valve opening causes the air valve projection 13 to approach the abutment 14 thereby producing 60 a choking effect which increases until the valve casing is in the full choke position shown in Figure 3, the richness of the mixture being correspondingly increased.

In Figs. 2 and 6, the fuel ducts 4 are 65 shown as radiating from the passage in the metering plug 5. In Figs. 3 and 5, I have shown the plug extending through a threaded aperture into the inner end of the main mixing chamber and provided with an additional fuel duct leading directly thereto. This arrangement is desirable under certain conditions. It is not essential that a metering plug shall be employed as the ducts of the proper bore may be drilled through the metal of the body as I have shown in Fig. 4. In the latter modification I have also shown the body provided with an additional sloping annular surface 20 which cooperates with an extension of the casing to form 70 an auxiliary air inlet valve which may be used in some instances. In the arrangement shown in Fig. 4, the parts are reversed from that shown in Figure 2, so that the air inlet is adjacent the manifold so that warm air 75 may be taken into the carburetor, and providing a muffling chamber 21.

Because of the characteristics of this carburetor whereby the degree of vacuum or sub-atmospheric pressure remains substantially constant in the main mixing chamber 80 at all engine speeds, and the mixture is maintained substantially uniform in density, it is particularly useful in carrying out my method of operating internal combustion engines which involves the admission of a combustible mixture to the engine cylinders at a uniform sub-atmospheric pressure and which is of less density than that at present employed, compressing the mixture to a higher compression than that now employed, and exhausting at substantially the same pressure as at present. By this method I obtain a higher mean effective 85 pressure and increase the power of the en- 90

gine with a proportionate decrease in the consumption of fuel. Furthermore I have found that the effective cross-sectional area of the main mixing chamber is much smaller than in any carburetors heretofore used.

I claim:—

1. A carburetor for internal combustion engines operating under varying loads and at variable speeds, having a main mixing chamber adapted to be placed in communication with the engine intake and a preliminary mixing chamber constructed for connection to a pipe leading to the fuel supply tank, an air intake valve for said preliminary mixing chamber and a throttle valve for said main mixing chamber, said valves being constructed to operate synchronously to admit a mixture to said main mixing chamber at substantially constant sub-atmospheric pressure at all speeds of the engine, and to cause a sub-atmospheric pressure in said preliminary mixing chamber which varies from a predetermined minimum at lowest speed to that existing 25 in the main mixing chamber at maximum speed.

2. A carburetor for internal combustion engines operating under varying loads and at variable speeds, having a main mixing chamber adapted to be placed in communication with the engine intake and a preliminary mixing chamber constructed for connection to a pipe leading to the fuel supply tank, an air intake valve for said preliminary mixing chamber and a throttle valve for said main mixing chamber, said valves being constructed to operate synchronously to admit a mixture to said main mixing chamber at substantially constant sub-atmospheric pressure at all speeds of the engine, and to cause a sub-atmospheric pressure in said preliminary mixing chamber which varies in proportion to the engine speed.

3. A carburetor for internal combustion engines having a main mixing chamber communicating with the engine intake, a preliminary mixing chamber having a liquid fuel inlet communicating therewith, an air valve controlling admission of air thereto, a throttle valve located between the two mixing chambers, means for operating the throttle and air valve simultaneously, said throttle being so constructed that the area of the passage between the two mixing chambers is varied on movement of the throttle in accordance with the normal variation in vacuum in the intake pipe so as to maintain a constant vacuum in the main

mixing chamber, while the air valve is constructed to concurrently and differently vary the area of the air intake port so as to maintain a varying vacuum in the preliminary mixing chamber.

4. A carburetor for variable speed internal combustion engines, comprising a body having a fuel inlet at one end, a main mixing chamber at the opposite end and a preliminary mixing chamber at an intermediate portion, said body also having fuel ducts connecting said fuel inlet with said preliminary mixing chamber and passages for connecting said preliminary mixing chamber with said main mixing chamber, a valve seat intermediate said chambers, a casing or sleeve movable longitudinally over said body and having valve members for simultaneously controlling in varying degrees respectively the admission of air to said preliminary mixing chamber and to the said passages connecting said chambers.

5. In a carburetor as set forth in claim 4, said body having a surface cooperating with said air intake valve to graduate the intake opening, said surface and said valve seat being inclined at different angles respectively to the longitudinal axis of the body.

6. In a carburetor as set forth in claim 4, said body having a surface cooperating with said air intake valve to graduate the intake opening, said surface and said valve seat being inclined to the longitudinal axis of the body, at angles respectively the tangents of which are substantially in the ratio of one to three.

7. A carburetor for internal combustion engines operating under varying loads and at variable speeds, having a main mixing chamber adapted to be placed in communication with the engine intake and a preliminary mixing chamber constructed for connection to a pipe leading to the fuel supply tank, an air intake valve for said preliminary mixing chamber and a throttle valve for said main mixing chamber, said valves being constructed to operate synchronously to admit a mixture to said main mixing chamber at substantially constant sub-atmospheric pressure of approximately one-half of atmospheric pressure at all speeds of the engine, and to cause a sub-atmospheric pressure in said preliminary mixing chamber which varies from a predetermined low pressure to that existing in the mixing chamber.

In testimony whereof I affix my signature.

WILLIAM H. COLLIER.
